Thomas B. Rider

By Adolph H. Danziger
Attorney.

UNITED STATES PATENT OFFICE.

THOMAS B. RIDER, OF LOS ANGELES, CALIFORNIA.

X-RAY TUBE.

1,400,001.

Specification of Letters Patent. Patented Dec. 13, 1921.

Application filed January 22, 1919. Serial No. 273,473.

To all whom it may concern:

Be it known that I, THOMAS B. RIDER, a citizen of the United States, residing at Los Angeles, in the county of Los Angeles and the State of California, have invented new and useful Improvements in X-Ray Tubes, of which the following is a specification.

My invention relates to improvements in X-ray tubes; and the objects of my improvements are to provide a cathode that will change the focal spot on the face of the anode at the will of the operator; to provide a cathode that will permit the operator to achieve this change of the focal spot on the face of the anode without any metallic aid from the outside; to provide a cathode that will accomplish the said change in focal direction by merely tilting the X-ray tube itself perpendicularly up and down; the invention consisting in the construction, combination and arrangement of the devices hereinafter more fully described and claimed and illustrated in the accompanying drawing, in which—

Figure I is an assembly of an X-ray tube with my device inserted.

Fig. II is a cross section of my device engaged with the cathode.

Fig. III is the same device disengaged from the cathode.

Fig. IV shows a disk with tapering holes at the bottom of the tubular metal sleeve.

Fig. V shows a view of the spiral ridge inside the tubular metal sleeve.

Fig. VI shows the spiral grooves in the weighted member.

In Fig. I, 1 designates the glass globe of the X-ray tube; 2 shows an extension glass tube closed at the end 3, surrounding a metal tube 4. The wire 5, fused into and through the closed end (3) outwardly forms one of the connections 6 for the electrical circuit and inwardly connects to the metal tube (4). An anode 7 is secured to the free end of the metal tube (4), having preferably a tungsten disk 8 inserted into the surface. Another extension glass tube 9 serves as a holder for the anticathode 10, which is connected to the anode (7) by the wire 11. A third extension glass tube 12 is provided with chemicals and serves as a regulator for the vacuum pressure within the X-ray tube; a wire 13 is connected to the outside of the tube (12) and projects toward the connecting metal end 14 of the

main cathode stem 15, which is inclosed in the extension glass tube 16.

In Fig. II, 17 shows an extra strong glass seal between the metal end (14) and the glass sleeve 18 inside the extension glass tube (16) to hold firmly the main cathode stem (15). The pin 19 runs through the glass sleeve (18) and the main cathode stem (15) to add to the firmness. A metal guard 20 protects the glass sleeve (18); 20_a is an oval spring set in the main cathode stem to keep in position the weighted member 21 from slipping back when the X-ray tube is in operation; 22 shows a groove cut in the weighted member (21) into which fits a pin 23; 24 is a tubular metal sleeve which telescopes the lower part of the weighted member and contains within a number of gradually declining spiral ridges 36 as illustrated in detail in Fig. V, which at a certain distance from the top engage the corresponding spiral grooves 35 in the lower part 34 of the weighted member 21 as illustrated in detail in Fig. VI; 25 is a metal guard; 26 is a chamber containing ball-bearings; 27 is the solid tubular part of the metal sleeve; 28 (Fig. III) shows the conical points of the eccentric cathode 29; 30 (Fig. IV) shows the series of tapering holes at the end of the solid part of the tubular sleeve (27); 31 is the centrally disposed axis, integral with the main cathode stem (15); 32 is a metal spring with a brush face or friction member 37, held in place by a screw 33 to prevent the eccentric cathode from moving in any direction while disengaged.

When a new focal spot on the anode is desired the cathode then being locked, of course, the operator tilts the X-ray tube holding it up in a vertical manner, making it stand on the end 14, or holding it in such a position to amount to such a standing on end, a slight agitation at once causes the weighted member 21 to move toward the guard 20, depressing the oval spring 20_a, and the weighted member, moving in a straight line upon the main cathode stem is held there by the pin 23; the weighted member engaging the metal sleeve 24 by the conjunction of the spirals and accelerated by the solid part of the metal sleeve 27 and the ball-bearing in the chamber 26, at once disengages the holes in the end 27 of the metal sleeve (Fig. IV) and leaves the eccentric cathode free upon its axis 31; while the metal spring prevents a move-

ment on the part of the cathode forward or backward. The operator is then certain that the cathode is at the same focal spot in relation to the anode as before.

- 5 The action disengages the recesses 30 in the disk face in the end 27 of the sleeve member 24 from the projecting members 28 on the cathode body 29. In this condition and at such a moment the cathode is free 10 to turn on the stem 15 except for the friction member 37 actuated by the spring 32 in the cathode member which prevents an undesired turning of the cathode member on the stem.
- 15 The X-ray tube is then turned to stand on end in the opposite direction. The spring or friction member 20₁ is designed so as to retard the falling of the weighted member while the sleeve member with the disk end 20 27 is so loosely mounted on the stem 15 that the recesses 30 engage with the projecting members 28 on the cathode 29 before the weighted member 21 reaches its termination in its movement toward the cathode.

- 25 While the sleeve member is so already engaged with the cathode, the weighted member still continues its movement toward the cathode. The weighted member 21, being prevented from turning 30 on the stem by the key and keyway engagement at 22 and 23, causes a turning of the sleeve member 24 and thereby a turning of the cathode on the stem since the sleeve is compelled to slide over the body 34 of the weighted member 21 in a spiral direction along the spiral ridges 36 and grooves 35.

- Through this operation, the cathode is turned and moved to a position to focus to a different point in the face of the anode 7.
- 40 The focus is in this manner changed at the will of the operator without any outside mechanism to help or influence the device for controlling the focus between the cathode and anode of such an X-ray tube.
- 45 All the operator has to do is to tilt the X-ray tube in the described manner for disengaging and engaging the different recesses and projecting members between the sleeve member and the cathode to cause the weighted member to accomplish the turning of the cathode when completing its fall in the direction toward the cathode, as described above.

In Fig. II, the cathode is illustrated in 55 engaged and operative position, set and adjusted to focus to a certain point in the face of the anode.

Having thus described my invention, I claim:

1. In an X-ray tube in combination with the cathode in such tube having its face disposed eccentrically on its supporting body on a centrally disposed stem in the tube, operating means disposed on the stem for a sliding movement, and means operatively engaged with the operating means for turning the cathode on the stem by such sliding movement.

2. In an X-ray tube in combination with the cathode in such tube having its face eccentrically disposed on its supporting body, a centrally disposed stem in the tube, a weighted member slidably disposed on the stem, and another member turnably and slidably disposed on the stem having means 75 engaging with the weighted member for a longitudinal and turning movement in relation to the weighted member.

3. In an X-ray tube in combination with the cathode in such tube having its face eccentrically disposed on its supporting body, a centrally disposed stem in the tube, a turning member disposed on the stem having means for engaging with the cathode when moved toward the cathode, a weighted member slidably disposed on the stem having spiral engaging means, and other spiral engaging means on the turning member corresponding to the spiral engaging means on the weighted member for producing a turning movement to the turning member when the weighted member is caused to slide on the stem.

4. In an X-ray tube, a centrally disposed cathode stem, a cathode turnably disposed on the end of the stem having its focusing face eccentrically disposed transversely to the stem, friction means disposed between the cathode and the stem, engaging means in the rear end of the cathode, turning means 100 on the stem having means for engaging with the engaging means on the rear end of the cathode, sliding means disposed on the stem, friction means disposed between the stem and the sliding means, and spiral engaging 105 means disposed between the sliding means and the turning means.

In testimony whereof I hereunto affix my signature in the presence of two witnesses.

THOMAS B. RIDER.
